P. CROSLEY, JR.
CURTAIN LIGHT.
APPLICATION FILED NOV. 7, 1918.

1,317,271.

Fig. 1.

UNITED STATES PATENT OFFICE.

POWEL CROSLEY, JR., OF CINCINNATI, OHIO.

CURTAIN-LIGHT.

1,317,271.

Specification of Letters Patent. Patented Sept. 30, 1919.

Application filed November 7, 1918. Serial No. 261,510.

To all whom it may concern:

Be it known that I, POWEL CROSLEY, Jr., a citizen of the United States, and a resident of Cincinnati, in the county of Hamilton and State of Ohio, have invented certain new and useful Improvements in Curtain-Lights, of which the following is a specification.

My invention relates to curtains, and more especially to carriage and motor vehicle back curtains which require some kind of aperture through which the occupant of the vehicle may look to the rear of the vehicle.

The object of my invention is to provide such an aperture in such a curtain with a transparent closure which may be very readily placed therein and which, when in place, will effectively close the opening against the weather.

My invention consists in the new and improved article of manufacture and in the combination of parts and in the details of construction and arrangement of parts as will hereinafter be more fully described and claimed.

In the drawing:

Figure 1 is a rear view of a part of the vehicle having a back curtain equipped with my invention;

Fig. 2 is a similar view showing a modification of the invention;

Fig. 3 is a partial sectional perspective view on an enlarged scale showing the right-hand side of one of the curtain openings and more clearly illustrating how my improved curtain-light is secured therein;

Fig. 4 is a partial front elevation of one of the curtain-lights;

Fig. 5 is a partial side elevation of the same; and

Fig. 6 is a partial rear elevation of the same.

As shown in Fig. 1, the back curtain 1 has the single aperture 2, which is considerably wider than it is high and which has its top arched as is usual in the design of curtain-lights. Ordinarily, there is simply such an opening 2 cut in the curtain and a sheet of suitable transparent material is permanently held in place over the opening by stitching it to the curtain around the edges of the opening. Such material may be glass or celluloid or other suitable transparent material. Usually it is celluloid or other flexible transparent material which is

readily torn or broken; and when thus disrupted its renewal is frequently neglected because in order to replace the ordinary light in this way in a practical manner, it is necessary to bring the vehicle to a repair shop and remove the top and have the new light stitched in place by an experienced workman.

It is the object of my invention to provide a light that is readily placed or removed, either when the vehicle top is first made, or to replace a torn or broken light with which the top has been provided in the ordinary manner.

With this object in view, I provide a sheet 3 of suitable flexible transparent material, preferably celluloid, a little longer and a little wider than the opening 2 and of approximately the same shape. Preferably, the sheet 3 is of such greater length and width as to overlap the material of the back curtain 1 about one-half inch all around the aperture 2. This sheet 3 is provided with bindings 4 preferably on both of its sides entirely around it next to its edges. These bindings are preferably of leather or other durable flexible material such as various imitations of leather used in the manufacture of vehicle tops and curtains; and the bindings along any given edge placed on opposite sides of the sheet 3 are stitched together and to the sheet 3 by parallel seams 5 very close to respective edges of the bindings.

These bindings thus reinforce and protect the somewhat brittle sheet 3 at its edges so that the article thus made up may be readily stored and handled without liability of damage.

At each vertical side a little below its middle, the sheet 3 has the patches 6 preferably of material the same as or similar to that of the binding 4; there being one of these patches on each side of the sheet 3 and the bindings 4 overlapping the patches at the respective sides of the sheet and terminating and having their ends coming close together about midway of the height of the patch. Through these flanking patches 6 and through the material of the sheet 3 between the patches is cut a slit 7 running from the coinciding edges of the sheet 3 and patches 6 horizontally inwardly for about one-half the transverse length of the patch 6 where it preferably terminates in a small circular opening 8. These parts 6 and the overlapping end parts of the bind-

ings 4 on the opposite surfaces of the sheet 3 are stitched together through the sheet by suitable seams 9 running around close to the edges of the patches and the seams 10 around close to the inner terminations 8 of the slits 7. Preferably, these patches are a little over one inch in width and height, and the slit 7 is about five-eighths of an inch long; terminating a little past the inner edge of the binding 4.

Just above the patch 6 the sheet 3 and its bindings have through them a perforation 11, and just below the patch 6 they have a similar perforation 12. Near one corner of the sheet 3 and its bindings 4 are perforations 13 through the sheet and bindings.

With the aperture 2 clear of any substantial obstruction, the curtain light thus made up of the sheet 3 and its bindings and patches is inserted into the aperture 2, so that all of its edge parts above the slits 7 lie against the surface of the back curtain 1 inside the vehicle; while the lateral edges of the aperture 2 are received in the slits 7 and the part of the curtain-light below the slits 7 lies outside the curtain 1 with its edge parts against the rear or outer surface of the back curtain 1 around adjacent to the edge of the aperture 2.

30 The curtain-light being thus placed in position so that its bound edge parts are adapted to fit snugly around adjacent to the edges of the aperture 2 inside and outside above and below the slits 7, respectively, as just described, there are passed through the perforations 11, 12 and 13, suitable clinch buttons 14 of any well-known kind. Such a button as is here shown comprises the round head 15 with thin pointed parallel shanks 16. 40 These have their shanks 16 passed inwardly through the perforations so that the heads 15 appear on the outside or rear of the back curtain; and the thin shanks 16 are pried and clenched against the inner surfaces. 45 Above the slits 7 the heads 15 will come directly against the surface of the curtain 1 and the clenching will be against the edge bindings 4 of the curtain-light inside the top; while below the slits 7 the heads 15 will come against the edge bindings 4 and the clenching will be against the inner surface of the curtain 1. One of these buttons is shown unclenched in the lower part of Fig. 5; and their fastened condition is indicated by the dotted lines in Fig. 3. It will be understood that any suitable fastening means may be substituted for the buttons herein shown as examples.

There is no essential difference in the 60 modification of Fig. 2. Here, the back curtain 1' has three apertures 2' in a row across it, each one being considerably higher than it is wide. For these, I prefer to provide the three curtain-lights constructed according to 65 my invention, each made up of the sheet 3'

of suitable transparent material with bindings 4' around their edges. The patches and other details being the same as in Fig. 1 they are designated by the same numerals.

A less expensive curtain-light is produced according to my invention by omitting the binding 4 above the slits 7 on one surface of the sheet and omitting the bindings below the slits 7 on the opposite surface of the sheet; the curtain-light thus constructed being applied to the apertures so that the surfaces without bindings come against the respective surfaces of the back curtain. It will be understood that either the design of Fig. 1 or that of Fig. 2, or any other design 80 that may be encountered, may be provided with curtain-lights either completely bound or partially bound, as just described. This partial binding, however, is more appropriate to the smaller lights as exemplified in 85 Fig. 2; and the complete binding is preferred where ample strength and durability of the article is desired preliminary to its installation. After the curtain-light has been placed and fastened as by the buttons 90 14, it will be sufficiently strong and durable, whether wholly or partially bound.

With the upper part of the light inside the back curtain 1 and the lower part outside, the water or other substance running down the outer surface of the curtain 1 readily passes on down over the surface of the sheet 3 to its lower part lying outside the curtain, and from there passes readily to the lower part of the curtain below the 100 sheet 3. On account of this relation of the light to the curtain surfaces, it is unnecessary to take any special precaution against the entrance of rain or other substances, and the simple fastening by means of the buttons 14 or the like is adequate to effectively close the aperture for all purposes in any kind of weather.

Where the vehicle curtain has been in use and its lights have been torn or broken, my 110 improved curtain-light is readily introduced by simply cutting away the old transparent material around close to the edges of the aperture without disturbing the material outside the edges where it is stitched to the 115 curtain. My improved curtain-light is then inserted into position, as hereinbefore described, with the upper part inside and the lower part outside the curtain and the buttons 14 or other suitable fastening means at 120 its corners and adjacent to its slits as described.

Certain variations are suggested herein, and it will be understood that others may be encountered in applying the invention to 125 a variety of vehicle tops and the like. It will also be understood that the invention is applicable to any similar situation, whether it be the back curtain or other curtain of any kind of vehicle, or any other structure where 130

a flexible element is to be provided with a transparent means for closing an aperture therein. Therefore, while certain constructional details are deemed preferable in connection with my invention, and I have shown and described these rather specifically in elucidating the construction and use of my invention, as is required, I do not wish to be understood as being limited to such precise 5 showing and description, but having thus fully described my invention, what I claim as new and desire to secure by Letters Patent is:

10

As a new and improved article of manufacture, a curtain-light comprising a sheet 15 of flexible transparent material having opposite slotted edges, a binding around the edges of said sheet, and patches stitched around the slits in said edges, thereby avoiding the necessity of stitching the curtain in applying said light, said binding and said patches being of flexible material.

POWEL CROSLEY, JR.
